CLAIM

The ornamental design for an HVAC control device, as shown and described.

DESCRIPTION

FIG. 1 is a perspective view of an HVAC control device, showing our new design;

FIG. 2 is a bottom view thereof;

FIG. 3 is a front view thereof; and,

FIG. 4 is a right side view thereof, the left side view thereof being a mirror image of the right side view thereof.

The broken lines of the preceding figures are for purposes of illustrating unclaimed portions of the HVAC control device and form no part of the claimed design.
